CONTAINER FOR GLASSES AND BOTTLES OR THE LIKE

Markku Vartiainen, Helsinki, Robert Paulig, Ostersund, and Matti Lahtinen, Helsinki, Finland, assignors to MRM-trading Ltd., Helsinki, Finland

Filed Nov. 7, 1973, Ser. No. 413,515

Claims priority, application Finland May 8, 1973

Term of patent 14 years

Int. Cl. D9—03

U.S. Cl. D9—223

FIG. 1

FIG. 2

FIG. 3

FIG. 4

FIG. 6

FIG. 5

FIG. 1 is a perspective view of a container for glasses and bottles or the like showing our new design, with the lid member removed and in an alternate condition;

FIG. 2 is a perspective view thereof with the like member in a partially closed condition;

FIG. 3 is a top plan view thereof;

FIG. 4 is a side elevational view thereof;

FIG. 5 is a bottom plan view thereof; and,

FIG. 6 is an end elevational view thereof.

In FIGS. 3 through 6, the lid member has been omitted for convenience of illustration.

We claim:

The design for a container for glasses and bottles or the like, as shown and described.
